DESIGN FOR A HANDBAG OR SIMILAR ARTICLE

Lilly Kertesz Rotkel, New York, N. Y.

Application November 17, 1944, Serial No. 116,387

Term of patent 7 years

(Cl. D87—3)

To all whom it may concern:

Be it known that I, Lilly Kertesz Rotkel, a citizen of no country, residing in New York city, county of New York, and State of New York, have invented a new, original, and ornamental Design for a Handbag or Similar Article, of which the following is a specification, reference being had to the accompanying drawing, forming part thereof, wherein

The rear of the handbag or similar article is substantially the same in appearance as the front.

I claim:

The ornamental design for a handbag or similar article, substantially as shown and described.

LILLY KERTESZ ROTKEL.
